CARPET SWEeper

Filed Oct. 10, 1932

INVENTOR,
ISRAEL C. CRANON.
BY Martin P. Smith, ATTY.

UNITED STATES PATENT OFFICE

2,012,658

CARPET SWEEPER

Israel C. Cranon, Los Angeles, Calif.

Application October 10, 1932, Serial No. 636,976

4 Claims.

(Cl. 15—41)

My invention relates to carpet sweepers particularly of the hand driven type and has for its principal objects, to generally improve upon and simplify the construction of the existing forms of carpet sweepers, to provide an improved form of handle that may be conveniently and comfortably engaged by the hand during the manipulation of the sweeper, further, to pivot the handle carrying bail to the body of the sweeper so as to prevent the rear portion of the body of the sweeper from swinging downwardly when said body is lifted from the floor and further, to mount the body of the sweeper upon two pairs of rollers, the rear pair having fixed axes and the front pair having vertically and horizontally moving axes, so that during operation of the sweeper the front portion thereof is permitted to move downwardly, thereby permitting the rotary brush to make direct contact with the surface over which the sweeper is manipulated.

Further objects of my invention are, to arrange between the swinging bearings for the front wheels and the body of the sweeper, springs that tend to resist the downward movement of the forward portion of the sweeper body as a result of manual pressure thereupon by the handle, which springs tend to normally force the front wheels into frictional contact with the ends of the cylindrical body of the rotary brush of the sweeper, and further, to mount the rotary brush so that it has a certain degree of horizontal movement toward and away from the front and back wheels of the sweeper and the ends of the brush body being supported by readily releasable means which when manipulated, enables the brush to be easily and quickly removed from the body of the sweeper.

A further object of my invention is, to provide a relatively simple, practical and efficient construction, whereby the end portions of the rotary brush are engaged by spring pressed front wheels and forcing into engagement with the rear wheels that have fixed axes, thereby producing increased friction and driving engagement between the wheels of the sweeper and the rotary brush.

Further objects are to provide means for mounting the wheels of the sweeper so as to eliminate axles that extend lengthwise through the body of the sweeper and to provide means whereby the bail carrying handle may be secured to the body while in a vertical position.

Further objects are to minimize the number and size of the openings in the upper portion of the sweeper body and to construct the body of the sweeper so that it is symmetrical in form

with closed rounded ends and sides and without abrupt corners.

With the foregoing and other objects in view, my invention consists in certain novel features of construction and arrangements of parts that will be hereinafter more fully described and claimed and illustrated in the accompanying drawing in which:

Fig. 1 is a top plan view of a sweeper constructed in accordance with my invention.

Fig. 2 is an elevational view of the outer end of the handle of the sweeper and showing the pistol grip thereof.

Fig. 3 is an enlarged cross section taken on the line 3—3 of Fig. 1.

Fig. 4 is an enlarged cross section taken on the line 4—4 of Fig. 1.

Fig. 5 is a vertical section taken on the line 5—5 of Fig. 3.

Fig. 6 is a detail section taken on the line 6—6 of Fig. 3.

Fig. 7 is an enlarged vertical section taken on the line 7—7 of Fig. 1.

Figs. 8 and 9 are plan views of modified forms of the outer end of the handle of the sweeper.

Referring by numerals to the accompanying drawing which illustrates a preferred embodiment of my invention, 10 designates the main body of the sweeper that is preferably formed of wood and the intermediate upper portion of said body is slightly arched in cross section and the sides of said body are curved downwardly as designated by 11.

Suitably secured to the ends of the arched body 10 are vertically disposed end walls 12, preferably of wood, and formed in the lower central portions of said end walls, are notches or openings 13 that are open at the bottom.

These openings 13 are for the accommodation of the end portions of a cylindrical brush body 14 and those portions of said brush body that occupy the notches 13 are reduced in diameter relative to the diameter of the body, as designated by 15.

Formed integral with the outer ends of the reduced portions 15, are friction discs 16 that are slightly larger in diameter than the diameter of the brush body 14.

Formed in the centers of the discs 16 and in longitudinal alignment with the axis of brush body 14, are recesses 17.

Brush body 14 carries tufts of bristles 18, thereby providing a cylindrical brush which during operation of the sweeper makes contact with the surface over which the sweeper is manipulated.

The corners between the lower edges of the

end walls 12 and the notches or openings 13 occupy a lower horizontal plane than the lower side edges of the sweeper body 10 and thus said lower edges gradually decline from the lower edges of the downwardly turned side portions 11 of body 10 toward the sides of openings 13.

Removably secured to the ends of body 10, are end caps 19 that are stamped or formed from sheet metal and the corners between the upper portions of said end caps and the vertical end walls thereof are rounded so as to eliminate sharp corners and give the entire body of the sweeper a symmetrical appearance.

The outer vertical portions of these end caps 19 are spaced apart from and occupy positions parallel with the end walls 12 and the wheels of the sweeper are positioned in the spaces between said end caps and end walls.

The rear wheels 20 of the sweeper are provided on their peripheries with tires 21 of rubber or rubber composition, said tires having flat peripheral portions that are adapted to directly engage the peripheral faces of the discs 16 on the ends of the brush.

Rear wheels 20 are journaled on pins 22 that are seated in the vertical walls of the end caps 19 and the inner ends of said pins being seated in the adjacent partitions 12 (see Fig. 6), or this construction may be reversed with the pins seated in the partitions 12 and projecting through the wheels into the end caps 19.

The vertically and horizontally movable front wheels 22 of the sweeper are practically identical in size and construction with the rear wheels 21, said front wheels having flat faced tires that engage the peripheries of the discs 16 and said front wheels are journaled on horizontally disposed pins 23 that have their outer ends seated in the lower portions of short links or arms 24.

The inner ends of the pins 23 occupy circular openings or recesses 25 that are formed in the outer faces of the end walls 12 and the diameters of these openings are three or four times greater than the diameters of the axis pins 23 (see Fig. 5), or if desired this construction may be reversed.

The upper ends of the short arms or links 24 are pivotally connected to the outer ends of longer arms or links 26, which latter project toward the vertical longitudinal center of the sweeper body and the inner ends of these longer links 26 are pivoted to pins 21 that are seated in the vertical walls of the end caps 19 or vice versa.

Rigidly secured in any suitable manner to the inner face of the vertical wall of each end cap 19, at a point above the end of the brush body, is one end of a bow spring 28 that extends outwardly and thence downwardly and the lower end of this spring is pivotally secured to link 24 or arm 26, preferably the latter as illustrated in Fig. 3 and at a point adjacent to the point of pivotal connection between said arm and link.

Thus each bow spring yieldingly resists the upward movement of the front wheel to which it is connected through links 24 and 26 and likewise these springs yieldingly resist downward movement of the front portion of the sweeper body.

Pivots connected to pins or rivets such as 29 that are seated in the upper central portions of the vertical walls of end caps 19 and on the exterior thereof, are the upper ends of depending arms 30 of resilient metal and carried by the lower ends of these arms are pins 31 that project inwardly through openings 32 that are formed in the vertical walls of the end caps and the inner

portions of said pins enter the recesses 17 in the discs 16, thereby providing supports for the rotary brush.

The openings 32 in the vertical walls of the end caps are considerably larger in diameter than the pins 31 and thus the latter may swing backwardly and forwardly through said openings 32 for a limited distance following corresponding movements of the rotary brush.

By engaging the lower ends of the springs 30 and pulling the same outward pins 31 are withdrawn from the openings 17, thereby permitting the rotary brush to be readily removed from its normal position within the sweeper body.

The parallel end portions of a bail 33 formed of a light weight metal rod or heavy wire, extend through relatively short slots 34 that are formed in the inwardly projecting portions of the end caps 19 and these parallel end portions are bent intermediate their ends so that the two portions of each end are disposed approximately 135° or 140° apart. The ends of these bent end portions of the bail are pivotally mounted upon pins 35 that are seated in the end walls 12 at points slightly above and to the rear of the notches or openings 13.

By thus pivoting the ends of the bail 13 to the sweeper body, the front portion thereof tends to move downwardly as a result of the greater weight in front of the pivot points 35 and consequently the rear portion of the sweeper tends to swing upward when the sweeper body is lifted upon the floor or other surface.

The slots 34 are formed in the end caps 19 so that the forward ends of said slots are positioned on the medial longitudinal line or major axis of the sweeper body and formed on the inner edges of the slots 34 adjacent to their inner ends, are outwardly projecting lugs 36 and when the bail is swung into a vertical position, as illustrated by dotted lines in Fig. 3, the parallel end portions of said bail ride past said lugs into the forward ends of slots 34 and they are retained in such positions as a result of the frictional engagement between the ends of the bail and said lugs.

Detachably secured in any suitable manner to the intermediate portion of bail 33, is a straight handle 37, preferably of wood, and secured to the outer end of said handle, is a depending pistol grip 38 that is manually engaged when the sweeper is operated.

In Fig. 8 I have shown the end of handle 37 provided with a knob 39 and in Fig. 9 the handle terminates in a D-shaped member 40 that may be conveniently gripped by the hand during sweeping operations.

Dust and sweepings receptacles 41, preferably formed of sheet metal, are arranged between the sides of the brush and the lower ends of the downwardly turned side portions 11 of body 10, said receptacles being pivoted on pins 42 that are seated in end walls 12. Projecting inwardly toward each other from the inner portions of these receptacles, adjacent to one of the end walls 12, are ears 43 and pivotally connected thereto, are upwardly projecting links 44. The upper ends of these links are pivotally connected to one end of a lever 45 that is fulcrumed at 46 to the adjacent end wall and secured to said lever between its pivot or fulcrum and the links 44, is a retractile spring 47, the lower end of which is suitably secured to the end walls 12.

The end of lever 45, opposite the end that is pivotally connected to links 44, extends upwardly

through a slot 48 that is formed in body 10 and the corresponding end cap 19 and the upper end of said upwardly extending portion of the lever is bent laterally to form a short horizontally disposed plate 49.

Under normal conditions spring 47 holds lever 45 and links 44 in the positions as illustrated in Fig. 4 and thus the receptacles 41 are positioned so as to close the bottom of the sweeper between the rotary brush and the lower ends of the downwardly curved side portions 11 of the sweeper body.

Under such conditions the outer portions of the bristles of the brush bear against the inner side walls of the receptacles and the dust and sweepings picked up by said bristles is delivered into said receptacles.

To swing the receptacles downward and effect a discharge of the sweepings therefrom, it is only necessary to press downwardly upon plate 49 on the end of lever 45, thereby swinging the same on its fulcrum and through links 44, the receptacles will be swung upon their axes so that the outside walls of said receptacles will move downwardly away from the lower edges of the side walls 11 of body 10.

During operation of the sweeper, the same is moved forwardly and backwardly over the surface that is to be swept and the downward and forward pressure applied to handle 37 causes the forward portion of the body of the sweeper to move downward into the position shown by dotted lines in Fig. 3 and which action is resisted by the tension of the springs 28.

As the sweeper moves forward, the front wheels 22 will automatically tend to move rearwardly and in so doing the peripheries of said front wheels will engage the peripheries of the discs 16 on the ends of the brush body and said discs will be forced into frictional engagement with the peripheries of the rear wheels 20.

As a result of this frictional engagement between the wheels 20 and 22 and the interposed discs 16, the brush will be rotated and the ends of the bristles will engage the surface over which the sweeper is moved and the dust or sweepings packed up by the brush bristles will be delivered into the receptacles 41.

In the operation of my improved sweeper, the greater portion of the sweeping action takes place during the forward movement imparted to the sweeper body, for during such forward movement the front portion of the sweeper body swings downwardly in the manner just described so as to cause the ends of the bristles in the brush to engage the surface over which the sweeper is moved and on the rearward movement of the sweeper body the front wheels 22 tend to move away from the discs 16 on the ends of the brush body, although such movement is yieldingly resisted by the springs 28 that exert downward pressure upon the front wheel carrying links 26.

An especially desirable feature of my improved sweeper is the mounting of the front wheels so that the front portion of the sweeper body may move downward relative to said wheels, further, the mounting of the front wheels on spring pressed links, whereby said front wheels may swing toward and away from the discs on the ends of the brush body and which discs are interposed between the swinging front wheels and the rear wheels having fixed axes and further, the mounting of the rotary brush in the sweeper and which mounting permits said brush to have a limited degree of horizontal movement back-

ward and forward between the front and rear wheels and which movement is provided for by the swinging resilient arms 30 carrying pins 31 that project through openings 32 in the end caps 19.

The entire body of the sweeper including the end caps, is devoid of abrupt corners, thereby presenting a symmetrical appearance and the entire housing of the sweeper is closed with the exception of the slots 34 for the accommodation of the bail 33 and the relatively short slot 48 for the accommodation of the upwardly projecting end of lever 45.

Thus it will be seen that I have provided a carpet sweeper that is relatively simple in construction, inexpensive of manufacture and very effective in performing the functions for which it is intended.

It will be understood that minor changes in the size, form, and construction of the various parts of my improved carpet sweeper may be made and substituted for those herein shown and described without departing from the spirit of the invention, the scope of which is set forth in the appended claims.

I claim as my invention:

1. In a carpet sweeper, a housing, a pair of rear wheels journaled on fixed axes on said housing, a pair of front wheels a trunnion forming the axis for each front wheel, a link carrying each trunnion, a second link pivotally connected to each first mentioned link, said second mentioned link being pivotally mounted on the housing of the sweeper, a spring arranged between each second mentioned link and a housing for yieldingly resisting upward swinging movement of said link, a rotary brush mounted for a limited degree of swinging movement in the center of said housing and discs on the ends of said brush which discs are interposed between said front and rear wheels.

2. In a carpet sweeper, a housing including a pair of end walls, a pair of rear wheels journaled on fixed axes within said housing, a pair of pivotally connected links arranged for swinging movement on each end of said housing, a trunnion carried by one link of each pair, front wheels journaled on said trunnions, springs arranged between said links and the housing for yieldingly resisting downward movement of the front portion of said housing and upward swinging movement of said links, the inner faces of the end walls of the housing being provided with short vertically disposed slots into which the outer ends of said trunnions project a rotary brush mounted for operation within said housing and discs on the ends of said brush, which discs are interposed between said front and rear wheels.

3. In a carpet sweeper, a housing having an arched upper intermediate portion and rounded front and rear portions, rounded caps arranged on the ends of said housing each rounded cap comprising a wall and a continuous flange projecting inwardly from the upper edge of said wall, which flanges throughout their lengths overlie and are secured to the ends of the sweeper housing, front and rear wheels journaled in the ends of said housing, said front wheels being mounted for vertical and lateral swinging movement relative to the rear wheels, a rotary brush mounted for operation in the center of the housing and discs on the ends of said brush, which discs are interposed between said front and rear wheels.

4. In a carpet sweeper, a wheel supported housing, rounded caps on the ends of said hous-

ing, the intermediate portions of which caps are provided with slots, the forward ends of which slots terminate on the medial longitudinal line of the sweeper body a bail having its end portions extending through said slots and pivotally connected to the ends of the sweeper body at points between the medial longitudinal line there-

of and the rear side of said sweeper body and a handle connected to said bail and a lug projecting from the inner edge of each slot immediately adjacent to the forward end thereof for engaging and holding the bail in a substantially upright position relative to the sweeper housing. 5

ISRAEL C. CRANON.
